CONNECTOR ENCLOSURE FOR USE ON POWER
LINE CONNECTORS

Robert Chieda, 3 Northgate, Westport, Conn.

Filed Feb. 5, 1964, Ser. No. 78,536

Term of patent 14 years

(Cl. D26—1)

FIG.1

FIG.2

FIG.3

FIG.4

FIG.5

FIGURE 1 is a perspective view of a connector enclosure for use on power line connectors, showing my new design, which defines a hollow interior volume for receiving an electrical connector therein and may be seen to be substantially symmetrical about a vertical, longitudinal median plane.

FIGURE 2 is a top plan view of my enclosure design.

FIGURE 3 is a full side elevation view of this enclosure, the two parts of the enclosure being at least partially separable along the vertical median line, which appears in the drawing.

FIGURE 4 is an end elevational view; and

FIGURE 5 is a bottom plan view of this enclosure design.

I claim:

The ornamental design for a connector enclosure for use on power line connectors, substantially as shown and described.
